UNITED STATES PATENT OFFICE

118,165

DESIGN FOR A PORTABLE AIR COMPRESSOR OR THE LIKE

August J. Lotz and Glenn W. Tammen, Chicago, Ill., assignors to Binks Manufacturing Company, Chicago, Ill., a corporation of Delaware

Application August 14, 1939, Serial No. 86,661

Term of patent 7 years

To all whom it may concern:

Be it known that we, August J. Lotz and Glenn W. Tammen, citizens of the United States, and residing at Chicago, county of Cook, and State of Illinois, have invented a new, original, and ornamental Design for a Portable Air Compressor or the like, of which the following is a specification, reference being made to the accompanying drawing, forming a part thereof.

The single figure of the drawing is a perspective view of the portable air compressor showing our new design.

Both sides, and both ends, of the compressor are alike.

We claim:

The ornamental design for a portable air compressor or the like, substantially as shown and described.

AUGUST J. LOTZ.
GLENN W. TAMMEN.
